TABLE

Donald A. Wallace, New York, N. Y.

Application August 13, 1946, Serial No. 132,490

Term of patent 3½ years

(Cl. D33—14)

To all whom it may concern:

Be it known that I, Donald A. Wallace, a citizen of the United States and resident of the city of New York, in the county of Queens and the State of New York, have invented a new, original, and ornamental Design for a Table, of which the following is a specification, reference being had to the accompanying drawings, forming a part thereof.

Fig. 1 is a perspective view of a table showing my new design.

Fig. 2 is a bottom view of the same.

Fig. 3 is an end view of the same.

I claim:

The ornamental design for a table, as shown.

DONALD A. WALLANCE.
